UNITED STATES PATENT OFFICE

2,570,268

INHALER

Ingram C. Pace, Livingston, Tex.

Application October 28, 1949, Serial No. 124,079

1 Claim. (Cl. 128—206)

1

This invention relates to an inhaler, and more particularly to an inhaler case having a removable inner case or filler.

It is an object of this invention to provide an inhaler of the kind to be more particularly described hereinafter having a filler slidably engaged in an outer case and an air vent valve actuatable upon sliding movement of the filler upon opening the cover or closure of the outer case.

Another object of this invention is to provide an inhaler of this kind having a spring-pressed, slidable insert or filler slidable, upon opening of the outer case, to a position wherein vent or air-passage openings in the filler and outer case will be in registry for the free passage of air through the filler. Upon closing of the outer case, the vent openings will be positioned out of registry, in valve-closing position, to retain the volatile medication within the inhaler casing.

Still another object of this invention is to provide an inhaler of this kind having removable pins engaging through the outer casing and in elongated slots in the filler for limiting the upward sliding movement of the filler upon opening of the casing.

A still further object of this invention is to provide an inhaler of this kind which is adaptable for an ornate, more or less expensive outer casing which may be retained as a refillable pocket case having changeable fillers which may be replaced when and as desired or required.

With the above and other objects in view, my invention consists in the arrangement, combination and details of construction disclosed in the drawings and specification, and then more particularly pointed out in the appended claim.

In the drawings:

Figure 1 is a perspective view of an inhaler constructed according to an embodiment of my invention;

Figure 2 is a longitudinal section taken on the line 2—2 of Figure 1;

Figure 3 is a transverse section taken on the line 3—3 of Figure 2;

Figure 4 is a fragmentary detail section, partly broken away, taken on the line 4—4 of Figure 1;

Figure 5 is a side elevation, partly broken away and partly in section, of the inhaler in the open, operative position.

Referring to the drawings, the numeral 10 designates generally a novel inhaler constructed according to an embodiment of this invention. The inhaler 10 is of a pocket type, being of a size to be readily carried about in the pockets of a user's clothing and is formed with an outer

2

casing 11 and an inner filler 12. Both the outer casing 11 and filler 12 are preferably made of transparent plastic material, though it is understood that various other materials of a more ornate nature may as readily be used.

The outer casing 11 is formed with a lower receptacle-like body 14 having a closure 15 hingedly mounted on one end wall thereof. The closure 15 is of a general cup shape, somewhat similar to the lower body 14 in an inverted position. A suitable hinge 16 connects the cover 15 to the body 14 for swinging from a closed position overlying the receptacle body 14 to an open position adjacent one side of the body and opening in the same direction, as clearly shown in Figure 5 of the drawings. A depending latch or arm 17 is carried by one side of the cover 15 and depends from the lower edge of the side wall opposite from the wall thereof which is hinged to the lower receptacle. A similar arm 18 is carried by the side wall of the receptacle 14 opposite from the respective hinge-bearing side wall. The arm 17 is adapted to frictionally engage the side wall of the receptacle 14 and the arm 18 engages the side wall of the closure 15 in side-by-side, adjacent relation for frictionally securing the cover 15 in its closed position, as readily noted in Figure 1 of the drawings.

The insert or filler 12 is formed of a hollow body 19 slidably engageable through the upper open end of the receptacle 14 to be retained therein. The filler body 19 may be filled with or contain medicament cartridges or pads 20 filled with any suitable or desired volatile liquid as desired for use with inhalers for nasal disturbances. The upper end of the filler body 19 is substantially cylindrical in configuration and having a substantially convex, curved or rounded upper end 20 to be seated on a nostril of the person using the device. An opening 22 is formed on the tip of the curved portion of the filler body 19 through which the medicinal vapors may pass when inhaled by the patient.

The medicinal, soaked cartridges 20 are initially engaged through an opening 24 in the bottom wall of the filler 12 into the filler and then the opening 24 may be sealed by the engagement therein of a closure plug 25. The closure plug may be sealed to the filler body or, in some instances, may be removably engaged in the opening 24.

The upper end of the filler body 12 will normally abut the lower side of the top wall of the closure 15, the filler body being extensible to a higher position upon opening of the closure 15. A pair of coiled springs 26 are engaged between

the lower end of the filler 12 and the inside surface of the bottom wall of the receptacle 14 for constantly biasing the filler upwardly to an extended position for normal use, as clearly shown in Figure 5 of the drawings.

The upward extension of the filler 12 is limited by a pair of limit pins 27 threadably engaged through opposite side walls of the receptacle and slidably engageable in elongated slots 28 in the opposite side walls of the filler 12. A pair of longitudinally-extending ribs 29 are formed on each end wall of the filler 12 defining therebetween open-ended air channels 30. An air vent opening 31 is formed in each end wall of the filler 12 and opens into the respective channel 30 between the filler and outer casing 11. Another vent opening 32 is formed in each end wall of the outer casing 11 for registry with the adjacent vent opening of the filler 12 in the raised or extended position of the filler. The pins 27, engaging in the slots 28 limit the extension of the filler to a position where the respective vents of the filler and casing are in transverse alignment to provide for the free passage of air through the filler when the inhaler is applied for use. Upon closing the cover 15, the top wall of the cover will engage the upper rounded end of the filler for pressing the filler 12 downwardly in the casing. Upon retraction of the filler against the spring tension, the vent openings 30 and 31 will be moved out of aligned registry, thereby limiting the free passage of air therethrough and thus extending the useful life of the filler 12 having the cartridges 20 soaked with the volatile medicinal fluid.

I do not mean to confine myself to the exact details of construction herein disclosed, but claim all variations falling within the purview of the appended claim.

I claim:

An inhaler comprising an outer receptacle open at one end, each of the side walls of said outer receptacle having vent openings adjacent to and spaced from the other end of said receptacle, an upstanding inner closed hollow body for containing a volatile medicament positioned within said outer receptacle and mounted therein for movement into and out of the open end of said receptacle, said body being of conical shape and forming a nasal portion to be engaged with a nostril of a patient, said nasal portion of said body having an opening therein through which the vapors liberated from the medicament pass when inhaled by the patient, a plurality of spaced vertically disposed coil springs resting upon the bottom of said receptacle and engageable with the lower end of said body for urging said body out of the open end of said receptacle, said body having an opening in each of its side walls registerable with the vent opening in the adjacent side wall of said receptacle upon execution of the movement of said body out of the open end of said receptacle, and a cup-shaped closure connected to said receptacle for swinging movement into and out of contact with the nasal portion of said body.
